UNITED STATES PATENT OFFICE.

JOSEPH ZANE, OF BOSTON, MASSACHUSETTS.

SPRING-COMPRESSION FAUCET.

SPECIFICATION forming part of Letters Patent No. 286,365, dated October 9, 1883.

Application filed January 20, 1883. (No model.)

To all whom it may concern:

Be it known that I, JOSEPH ZANE, a citizen of the United States, residing at Boston, in the county of Suffolk and State of Massachusetts, have invented certain new and useful Improvements in the Manufacture of Spring-Compression Faucets; and I do hereby declare that the following is a full, clear, and exact description of the same, reference being had 10 to the accompanying drawings, forming a part of this specification.

In the manufacture of self-closing spring-faucets which employ the Jenkins invention, patented June 27, 1865, of a steep-pitched screw or cam with a twisting handle, or of 15 spring-compression faucets which employ a slower-pitched screw and twisting handle, both of which sorts of faucets are spring-compression faucets, some difficulties have always 20 existed in obtaining a construction which shall be at once economical and have the property of protecting the cams or screws from detachment from their normal opposition to the spring, which may, and often does, happen when there is a shoulder adjacent to the 25 working parts, where a prop may be inserted to take the spring-bearing off the cams or screws. Hitherto these faucets in their best form have been made with cut cams or screws, 30 and with a cylindrical neck on the handle; and the best construction for the slow movement has been the "crown-snail" form of cams, and for the quick movement the quick-screw, usually of three or four threads. In this in- 35 vention I propose to employ the crown-snail movement, as in the Roach patent of September 6, 1868, for both the quick and slow inclines. In this invention I make the T-handle with a large central bulb, containing 40 a recess deep enough to completely or very nearly cover the cams both of the neck and handle when the valve is open, and in the depth of this recess, at or near the upper part of the handle, the downwardly-projecting 45 cams, counterparts of those which form the crown-snail on top of the neck of the faucet are located. These are preferably cast *in situ*, but may be made separately and soldered in, or may be cut. The bulb must be large enough 50 and the recess deep enough to practically cover the cams on the neck of the faucet, which

form the crown-snail, when the handle is so turned as to give the valve its greatest lift. The sides of the recess in the bulb of the handle are more sharply tapered than usual in 55 castings, so that the pattern may draw, and the casting is done in a two-part mold divided transversely of the recess, with the recess next the sand of one part. The cap of the faucet is cast in a two-part mold divided transversely 60 of its axis, and with its axis vertical instead of horizontal, as has hitherto been usual, and by this form of parts and method of making much of the cutting and filing or milling is 65 saved, for the cavity for the stem-packing is 70 nearly made in the mold, and a part of the stemway is also made at the other or upper extremity of the neck of the cap. The crown-snail also, which terminates the neck of the faucet upward, is completely formed 75 in casting, and requires no finish. In case the slow incline is employed, it is desirable 80 to have stops to check the revolution of the handle, so that it will not jump the cams while in the employment of the quick screw 85 or cams. The compression of the spring has hitherto been sufficient as a stop for all practical purposes. I make the stops, as well as 90 the cams, by casting. They are on the outside, radially, of the crown-snail, and are little projecting blocks at the highest part of the inclines on the neck and at the lowest part of the inclines in the handle, one or both sets of them projecting toward the other. I prefer to have the stops on the neck flush with 95 the upper surface of the crown-snail for constructive reasons. By this form of construction I am enabled to save about ten per cent., or more, of the cost of a faucet, and make it just as good and not inferior in appearance. 100 The bearing-surfaces, also, having their natural skin, will be harder and far more durable, and from the fact that the cams are completely inclosed by the bulb of the handle, there will be greater resistance to spreading radially 105 than in the old form, and from the fact that they will be united to the inner walls of the recess they can hardly be broken off by any violence of twist to the handle.

In the drawings, Figure 1 is a vertical section of a spring-faucet, not self-closer, with the valve raised. Fig. 2 is a vertical section of

the cap and handle parts of the same faucet as they would be valve closed. Fig. 3 is a perspective of the cap of the same faucet. Fig. 4 is a perspective of the handle of the same faucet, showing the interior. Fig. 5 is a top plan of the cap and neck of the same faucet. Fig. 6 is a bottom plan of the handle of the same faucet. Fig. 7 is a vertical section of the spring-faucet self-closer with the valve raised. Fig. 8 is a vertical section of the cap and handle parts of the same faucet as they would be valve closed. Fig. 9 is a perspective of the cap of the same faucet. Fig. 10 is a perspective of the handle of the same faucet, showing the interior. Fig. 11 is a top plan of the cap and neck of the same faucet. Fig. 12 is a bottom plan of the handle of the same faucet. Fig. 13 is a vertical section of a rough casting of the cap of Figs. 1, 2, 3, 5, showing the cast recesses at top and bottom.

In the drawings, A is the handle. It is made with a very considerable enlargement, B, at the place where it engages with the neck of the cap. Within this enlargement is a recess, C. The handle is bored through this recess for the valve-stem, as seen at D, and around this way for the valve-stem are disposed, at the deepest part of the recess, cams E, substantially of a spiral cut. The recess C is deep enough to extend so far below the cams or crown-snail on the neck of the faucet as to completely cover them at the highest lift of the handle, and as the swell in which the recess is located is made of globular form, and there is no shoulder on the neck of the faucet, there will be no place for the insertion of a prop or chip to hold up the handle, and so let the faucet leak, whether it be desired to insert the prop or chip under the handle in the lower part of the interval between the cams K, or between a shoulder on the handle and a shoulder on the neck, as is frequently done. Unless the cams are without the angle of repose—say steeper than about one in four—the faucet will not be a self-closer, and in such case it will be advisable to provide stops to check the rotation of the handle. These stops are small projections F at the lowest point of the inclined cams of the handle.

The interior of the recess and the cams and stops may be left as they come from the sand, for castings can now be made smooth enough for this work without finish other than brushing, and the cams will wear better with their natural skin than if this be removed. The handle is cast in a two-part mold which separates transversely to the axis of the recess, and thus is in a proper position to draw.

G is the cap of the faucet. It has at its lower end a shouldered screw-neck, H, to unite it with the body of the faucet, and there is a recess, J, at the center of this lower part, for the reception of the stem-packing. Above the shoulder the cap tapers upward into a neck, O, which terminates upwardly in upwardly-projecting cams K, forming what is technically

called in these faucets a "crown-snail," of which the cams in the handle are counterparts. In case the stops are desired, they are placed as shown at L, so as to engage with the stops F of the handle at the proper time in the rotation of the handle and prevent the overriding or jumping of the cams. This cap is cast in a two-part mold, with the parting transverse to the axis of the cap, as shown by the dotted line x x, and there is a recess formed at the upper end of the cap, as shown at M, for part of the valve-stem way. All the finish that this cap requires is to be turned or milled on the outside, to be bored for the valve-stem, and to have the screw cut which unites it to the body of the faucet. I cast the recesses in the cap as deep as they can conveniently be cast without coring, which would be too expensive, and the cams come smooth enough for this kind of work. This construction is intended to be employed in that class of faucets in which a spring is employed to drive the valve to its seat and the cams to lift the valve from the seat, in which the rotation of the handle does all the work of lifting the valve and the spring does all the work of driving and holding the valve against the water-pressure. Fig. 7 shows in section such a faucet having the quick movement or steep cams essential to a self-closer, and Fig. 1 shows such a faucet having the slow movement. They both are spring-compression faucets. In such faucets the valve-stem passes through the axis of the cap and through the handle, and is confined to the handle by a washer or annulus, against which the handle lifts in its rise when rotated over the cams. This construction is shown in the Roach patent, already referred to.

It will be seen that what is now shown relates to details of construction, whereby a better article and a cheaper article can be made—better because more durable, cheaper because requiring less material to start with and less labor and wear of tools to finish and complete—and these results are reached by change of form of the working and other adjacent parts, whereby certain shop appliances may be employed in the manufacture which could not be employed with the old form. These results were only reached after a long series of trials and studies, and it is believed that they will be found to have greatly advanced the manufacture of faucets of this class.

I claim as my invention and desire to secure by Letters Patent—

1. The combination of the cap G, carrying at its upper end a cast crown-snail, K, with a handle, A, carrying a counterpart crown-snail, E, in a recess, C, of the handle, substantially as described.

2. The handle A, having cams E, provided with stops F, in combination with the cap G, carrying the crown-snail K, provided with stops L, substantially as described.

3. In a self-closing faucet having a twisting handle, the neck O, provided with the crown-

snail K, in combination with the handle A, recessed to receive the lifting-cams, and provided with the bulb B, which is sufficient in depth to completely cover the cams on the crown-snail of the neck, substantially as described.

4. The handle A, recessed to receive the

lifting-cams, and having cams E within the recess, substantially as described.

JOSEPH ZANE.

WILLARD C. FOGG.

It is hereby certified that in Letters Patent No. 286,365, granted October 9, 1883, upon the application of Joseph Zane, of Boston, Massachusetts, for an improvement in "Spring Compression Faucets," errors were committed in the printed specification requiring the following corrections to be read therein, viz: A *comma* should be inserted after the word "cams" in line 74, page 1; the period after the word "cams" in line 76, page 1, should be erased and *a comma* inserted, and the following word "The" read *the*, thus making the sentence continuous; and that the speeification should be read with these corrections therein, to make it conform to the record of the case in the Patent Office.

Signed, countersigned, and sealed this 30th day of October, A. D. 1883.
